DRAWER PULL

Alfred H. Anderson, Youngstown, Ohio, assignor
to The General Fireproofing Company, Youngs-
town, Ohio, a corporation of Ohio

Application October 7, 1953, Serial No. 27,093

Term of patent 14 years

(Cl. D10—8)

To all whom it may concern:

Be it known that I, Alfred H. Anderson, a citizen
of the United States, residing at Youngstown,
in the county of Mahoning and State of Ohio,
have invented a new, original, and ornamental
Design for a Drawer Pull, of which the following
is a specification, reference being had to the accompanying
drawing, forming part thereof.

Figure 1 is a perspective view of a drawer pull
showing my new design.

Figure 2 is a top plan view.

Figure 3 is a front elevation.

Figure 4 is a rear elevation.

The broken line segment in Figure 1 depicting
a portion of a drawer is for illustrative purposes
only.

I claim:

The ornamental design for a drawer pull, as
shown and described.
